UNITED STATES PATENT OFFICE

MACIEJ BABIARZ AND JOSEPH BABIARZ, OF SPOTSWOOD, NEW JERSEY

WINDOW CONSTRUCTION

Application filed March 3, 1930. Serial No. 432,763.

This invention relates to improvements in windows, and it is the principal object of our invention to provide sashes for windows which can readily be removed from the window frame for cleaning and other purposes.

Another object of our invention is the provision of a window, the sashes of which are normally held in adjusted or closed position by means of panels which effectively prevent the sashes from being disengaged from the frame, and the entrance of air-drafts and moisture into a room.

A further object of our invention is the provision of window sashes swiveling about their centre pin engaged in holes in the window frame communicating with a groove allowing a withdrawal of the pin and removal of the window from the frame.

A still further object of our invention is the provision of a window having movable sashes with screens removably adjusted relatively to the sashes so that the entrance of insects etc., is positively prevented.

In the accompanying drawings, forming a material part of this disclosure:

Fig. 1 is a front elevation of a window constructed according to our invention.

Fig. 2 is a sectional side elevation thereof illustrating the screen adjustment.

Fig. 3 is a fragmentary inner view of a window frame.

Fig. 4 is a fragmentary edge view of a window sash.

Fig. 5 is a fragmentary front elevation of a window screen.

As illustrated, a window frame 10 of well known construction has hinged thereto at its inner face, as at 11, 11', an upper panel 12 and a lower panel 12' each provided with an operating knob 13 on its outer face.

The window sashes 14, 14', in approximately their middle are provided with pins 15 adapted to engage in grooves 16 formed in the sides of the window frames behind the panels and communicating with bores or holes 17 into which the pins or pintles 15 enter after being slidably engaged in grooves 16. Near their upper ends the sashes are equipped with yielding rubber cushions 18.

The lower sash 14' is equipped at its front

with a grip or handle 19, and screens 20 and 20', are provided in frames 21, having their ends cut away as at 22 and equipped with pivot pins 23.

In operation, the pins 15 of the sashes 14, 14', are introduced into groove 16 and slide within the same until they reach holes 17 so that then the sashes are now pivotally attached to the frame and the panels 12, 12', are turned about their hinges to engage the inner faces of the frame.

If it is desired to remove one or the other window, the panels are opened and the pins 15 slide out of groove 16 so that the window may readily be cleaned.

The screens 20 are inserted in the following manner: The lower window is partly opened to assume the position shown in Figure 2, and the frame of the lower screen 20', is engaging with its cut out edges 22 the sash of the window, while its pin 23 is engaged in groove 16 and its lower frame rests on the window sill, as indicated at 24. The upper screen 20 with the sash partly opened as shown in Figure 2, rests with its frame 21 engaging the lower frame of the upper sash, and with its inner frame upon the sash of the lower window, suitable handles being provided on the screen frame. It will be clear that the panels when closed will hold the sash in place and prevent draft and moisture entering a room.

It will be understood that we have described the preferred form of our device only and that we may make such changes therein as come within the scope of the appended claims without departure from our invention.

What we claim as new, and desire to secure by Letters Patent is:

1. In a window of the class described, including tiltable sashes, an upper screen resting on the upper frame bar of the lower sash and engaging the lower frame bar of the upper sash, and a screen vertically disposed with its lower frame bar on the window sill and engaging with the cut-away edges of its upper frame bar the side bar of the lower window sash in its inclined position.

2. In a window as described including its

frame having grooves formed therein and tilttable sashes, a screen vertically disposed with its lower frame bar on the window sill, a pin on the upper frame bar of said screen
5 adapted to engage the groove in the window frame, said screen engaging with the cut-away edges of its upper frame bar the side bars of the lower window sash in its inclined position for allowing a ventilation of the
10 room in the tilting position of the sashes and preventing the ingress of moisture, dust and insects.

Signed at New York, in the county of New York, and State of New York, this 21st day
15 of February, A. D. 1930.
